Charles David Williams.

BY

G. M. Fairbank
ATTORNEY

UNITED STATES PATENT OFFICE.

CHARLES DAVID WILLIAMS, OF NEW YORK, N. Y., ASSIGNOR TO ADAMS-WILLIAMS MANUFACTURING CORPORATION, A CORPORATION OF NEW YORK.

CONVERTIBLE AUTOMOBILE-BODY CONSTRUCTION.

1,377,166.

Specification of Letters Patent.

Patented May 3, 1921.

Original application filed January 11, 1916, Serial No. 71,516. Divided and this application filed August 22, 1919. Serial No. 319,057.

To all whom it may concern:

Be it known that I, CHARLES DAVID WILLIAMS, a citizen of the United States, and a resident of New York, borough of Manhattan, in the county of New York and State of New York, have invented certain new and useful Improvements in Convertible Automobile - Body Constructions, of which the following is a specification.

10 This application is a division of my prior co-pending application, Serial No. 71,516 filed January 11, 1916, and the present invention is an improvement on the general type of construction shown in my prior 15 Patents 1,151,314 and 1,151,315 issued August 24, 1915. These patents cover body constructions in which panels with rigid frames and transparent body portions are detachably secured to the upper edge of the vehicle 20 body wall sections to extend to the vehicle top and thus permit of the converting of the body from an open touring car type to a closed or limousine type at will.

The object of my present invention is to 25 provide a simple, inexpensive, and easily applied and operated means for rigidly but detachably securing the panels in place, permitting their easy and quick removal, and presenting an attractive appearance 30 both when the panels are in place and when removed.

Each panel corresponds in a general way 35 to the width of a corresponding stationary or movable body wall section and is provided with a plurality of depending lugs by means of which the panel is detachably secured in place. By means of my invention, I provide each body wall section with corresponding spaced sockets within which the 40 lugs may be clamped so that the panel will be effectively secured and held against rattling. Although my invention may assume various different specific forms, I have illustrated but one in the present application 45 and this is in the form of a molding strip adapted to be secured to the upper edge of the body wall section. As an important feature of this form, the molding strip may be made up in long strips and 50 may be cut into sections of the desired length corresponding to the length of the body wall sections to which they are to be applied. As a further important feature I provide a clamping screw mounted to in-

tersect a socket and carried by a supporting plate on one side of the wall and anchored to the opposite side.

In the accompanying drawings:

Figure 1 is a perspective view of a portion of a vehicle body, showing a door partly open and the panels secured in place.

Fig. 2 is a top plan view of one of the molding strips, the panel being removed.

Fig. 3 is a transverse section on the line 3—3 of Fig. 2, and

Fig. 4 is an edge view of the molding strip and panel in spaced relationship.

I have illustrated my invention as applied to a vehicle body having one or more stationary wall sections 10 and one or more 70 movable wall sections or doors 11, each being provided with its corresponding panel, which includes a transparent body portion 12, a rigid frame 13, and depending lugs 14. The completed body wall section 75 includes the usual wood frame 15, with an upper portion or strip 16, presenting substantially flat straight sides. In one vertical edge (preferably the outer one) of the strip 16, there are cut recesses or sockets 80 17 spaced at the proper distance apart and of the proper size to receive the lugs 14 of the corresponding panel. Secured to the surfaces of the strip 16, opposite to the sockets 17, is a clamp carrying member 18, 85 having a threaded aperture receiving the clamping screw 19, which extends in a substantially horizontal direction and when in operative position, intersects the corresponding socket 17. For securing the 90 socket carrying member 18 in position and for strengthening and reinforcing the wood frame strip 16, I provide a pair of screw bolts 20 extending substantially parallel to the clamping screw 19 and upon opposite 95 sides of the latter, and of the socket 17. For anchoring the opposite ends, a metal strip 21 extends along the side of the strip 16 opposite to the strip 18. Screw bolts 20 are of a length substantially equal to the 100 total thickness of the strips 16, 18, and 21, and their ends are threaded into the strip 21 so that when tightened, they hold the structure together. If the sockets 17 be 105 in the side surfaces of the strip 16, the anchoring strip 21 serves as a side wall for the socket and against which the clamping screw may force the lug. If the sockets be

cut in the strip 16 intermediate of the side edges thereof, the strip 21 will obviously reinforce and back up the portion of the strip 16 against which the lug is forced by 5 the clamping screw.

The strip 16 may constitute an integral part of the original wood frame of the body wall section and the strips 18 and 21 may be directly secured to the outer sides thereof 10 or portions may be cut away so that the strips 18 and 21 are embedded in the frame and thus do not project beyond the planes of the opposite sides of the door frame as indicated at the lefthand side of Fig. 3. 15 The strips 16 may be made separate from the frame of the door and may have the strips 18 and 21 secured thereto, so as to make a molding strip and this complete strip may be secured to the upper edge of 20 the body wall section in any suitable manner, as for instance, by screws 22. Although these may be placed at any desired points along the length of the molding strip, I find with a minimum number of screws that 25 the greatest rigidity results from using a pair of these screws 22 for each socket 17 and placing them between the clamping screw 19 and the transverse bolts 20. The strip 16 preferably has an upstanding ridge 30 or bead 23 on its upper surface along the inner sides of the sockets 17 so as to lie closely adjacent to the inner surface of the frame of the panel and project above the lower edge of the latter, and thus aid in 35 preventing rain or wind from beating under the edge of the panel.

The complete molding strip or the separate component parts 16, 18, and 21 thereof, may be made up in long sections and may 40 be cut to the length desired when to be applied or assembled. The metal facing strips 18 and 21 by extending the entire length of the molding strip, provide a uniform attractive appearance and tend to reinforce or 45 strengthen the strip 16 but it will of course be evident that these strips 18 and 21 might be made in shorter sections and each applied only along the portions adjacent to the sockets. The molding strip may be applied 50 upon the molding strip already in place if the vehicle body have such, or as a substitute for the old molding upon the removal of the latter. As previously indicated, where the invention is to be incorporated in 55 the vehicle body at the time the latter is designed and built, the sockets or recesses which receive the depending lugs of the panel may extend down into the wall rather than merely into the molding. The molding 60 might be a plain flat strip either secured to or extending over metal sockets set into the wall and the fastening screws 19 might extend through the wall itself rather than through the molding so as to engage with 65 and lock the lugs 14 and hold the panel in

position. The sockets may be cut vertically or at any desired angle to the vertical so as to tilt the panel and insure the proper engagement of the upper edge thereof with the vehicle top, although preferably the side 70 edge of the strip 16 is planed at the desired angle before the strip 21 is applied so as to give the desired tilt to the panel.

Having thus described my invention what I claim as new and desire to secure by Letters Patent is:

1. A convertible automobile body including a wall section, having a wooden frame presenting a lug receiving opening in the upper edge thereof, a reinforcing member 80 secured to said frame at one side of said opening, a separate reinforcing member secured to the opposite side of said frame, and having a threaded passage therethrough, a clamping member extending 85 through said passage into said opening, and means for rigidly connecting said reinforcing members.

2. A convertible automobile body including a wall section, having a wooden frame 90 presenting a lug receiving opening in the upper edge thereof, a reinforcing member secured to said frame at one side of said opening, a reinforcing member secured to said frame at the opposite side of said 95 opening, and having a threaded passage therethrough, a clamping member extending through said passage into said opening, and a pair of transversely extending screw bolts for rigidly connecting said reinforcing members.

3. A convertible automobile body, including a wall section having a wooden frame presenting a lug receiving opening in the upper edge thereof, a pair of reinforcing 105 strips upon opposite sides of said frame, a pair of screw bolts extending through said frame and connecting said reinforcing strips together, and a clamping screw extending through one of said reinforcing strips and 110 intersecting said lug receiving opening.

4. A convertible automobile body, including a wall section having a wooden frame presenting a lug receiving opening in the upper edge thereof, a member upon one side 115 of said frame opposite to said opening, a pair of anchoring bolts extending through said member and said frame upon opposite sides of said opening, and a clamping screw extending through said member and intersecting said opening.

5. A convertible automobile body, including a wall section, a removable panel having depending lugs and a molding strip separate from said wall section but secured to 125 the upper edge thereof, and presenting sockets adapted to receive said lugs, said molding strip including a wood strip having the sockets therein, and reinforcing strips extending lengthwise thereof upon opposite 130

sides, one of said reinforcing members carrying clamping screws adapted to intersect said sockets.

6. A molding strip adapted to be secured to a vehicle body wall section, and including a wooden strip and a pair of metal reinforcing strips upon each side thereof rigidly secured together, said wooden strip having lug receiving apertures therein, and one of 10 said reinforcing strips having clamping screws intersecting said apertures.

7. A molding strip adapted to be secured to an automobile body wall section, including a wooden strip having sockets in one 15 side edge thereof, a reinforcing strip secured to said edge and forming a side wall for said sockets, clamping screws extending through said wooden strip from the opposite side and intersecting said sockets, and means 20 presenting threaded apertures for supporting said clamping screws and secured to said wooden strip.

8. A convertible automobile body, includ-

ing a wooden frame, having a lug receiving socket in one side surface thereof, a reinforcing strip secured to said surface and forming a side wall for said socket, a reinforcing strip secured to the opposite side of said frame, means upon opposite sides of said socket for securing said strips together, and 25 a clamping screw intersecting said socket for forcing a panel lug against said first mentioned reinforcing strip.

9. An article of manufacture, a molding strip adapted to be secured to the upper 35 edge of an automobile body wall section, and having a pair of vertically disposed lug receiving sockets, and a pair of clamping screws carried by said strip adapted to intersect said sockets to clamp panel lugs 40 therein.

Signed at New York city, in the county of New York, and State of New York, this 19th day of August, A. D. 1919.

CHARLES DAVID WILLIAMS.
